(57) **CLAIM**

We claim the ornamental design for a folding camp stove, as shown and described.

DESCRIPTION

FIG. 1 is a perspective view of a folding camp stove, illustrated in an assembled position, showing our new design;

FIG. 2 is an exploded perspective view thereof;

FIG. 3 is a front elevational view thereof, illustrated in the assembled position, the rear elevational view being a mirror image thereof;

FIG. 4 is a left-side elevational view thereof, illustrated in the assembled position, the right-side elevational view being a mirror image thereof;

FIG. 5 is a top plan view thereof;

FIG. 6 is a bottom plan view thereof;

FIG. 7 is an alternate perspective view thereof, illustrated in a partially collapsed position;

FIG. 8 is a top plan view thereof, illustrated in a fully collapsed position;

FIG. 9 is a top plan view thereof, illustrated in an alternate collapsed position; and,

FIG. 10 is a bottom plan view thereof, illustrated in the fully collapsed position.
